UNITED STATES PATENT OFFICE.

HERBERT W. SELLNER, OF FARIBAULT, MINNESOTA.

DESIGN FOR A COASTER-CAR.

52,810.

Specification for Design.

Patented Dec. 24, 1918.

Application filed May 17, 1917. Serial No. 169,348. Term of patent 3½ years.

To all whom it may concern:

Be it known that I, HERBERT W. SELLNER, a citizen of the United States, residing at Faribault, in the county of Rice and State of Minnesota, have invented a new, original, and ornamental Design for a Coaster-Car, of which the following is a specification, reference being had to the accompanying drawing, forming a part hereof.

My design comprises a child's toy vehicle or coaster car of graceful and artistic appearance, the running gear whereof are set at a rakish angle, and the body or seat whereof is of artistic and conventional outline.

In the drawings—

Figure 1 is a longitudinal side elevation of my design.

Fig. 2 is a top plan, and

Fig. 3 is a bottom plan of my design.

What I claim is:

The ornamental design for a coaster car shown and described.

In testimony whereof, I have hereunto set my hand and seal, at Faribault, Minnesota, the 14th day of May, 1917.

HERBERT W. SELLNER. [L. S.]
